UNITED STATES PATENT OFFICE.

EIGIL AAGE HANSEN, OF FREDERIKSBERG, NEAR COPENHAGEN, DENMARK.

LOW-WATER-ALARM APPARATUS FOR STEAM-BOILERS.

1,312,175.

Specification of Letters Patent.

Patented Aug. 5, 1919.

Application filed December 22, 1917. Serial No. 208,374.

To all whom it may concern:

Be it known that I, EIGIL AAGE HANSEN, a subject of the King of Denmark, residing at Frederiksberg, near Copenhagen, Denmark, have invented new and useful Improvements in Low-Water-Alarm Apparatus for Steam-Boilers; and I do hereby declare the following to be a full, clear, and exact description of the same.

10 The present invention relates to an improvement in alarm apparatus for indicating low water in steam boilers. The apparatus comprises a casing connected with the water body of the boiler, which casing is normally filled with stagnant, relatively cold water, but when the water in the boiler falls below a predetermined level the casing is filled with hot steam, actuating a thermostatic device in the casing to permit the 15 steam to escape to a whistle or other signal apparatus.

The characteristic feature of the present invention is the use of a disk of thin metal or a diaphragm instead of the ordinarily used 20 fusible plug or valve, which disk closes a small aperture and can be pierced by a pointed stylus or the like which is actuated by the thermostatic device.

The invention is shown in the accompanying drawing in a sectional view. *a* designates the casing, *b* a plug tightly screwed into the same and provided with a stud *c* carrying the bimetallic spring *d*. The free end of the latter is positioned to actuate one 25 arm of an angle lever *e* pivoted on the plug and the other arm of the lever is positioned to press a pointed stylus *f* or the like upward in a bore in the plug *b* as shown. The whistle *h* ends in a sleeve which may be 30 screwed over a nipple on the plug *b* and tighten a disk *g* of thin lead plate or other suitable material firmly against the end of the nipple, so that the bore containing the stylus *f* is tightly closed.

45 If the spring *d* is heated and the metal which has the greatest expansion is on the outside of the same, the spring will cause the angle lever *e* to press the stylus *f* upwardly, and the latter will pierce the lead plate so that the steam can flow to the whistle.

50 The bimetallic spring, shown as one form of thermostatic means which may be used, has the advantage that it occupies but a small space so that the apparatus is small and compact in construction; but the inven-

tion is not limited to the use of such a spring, as I may employ any suitable means which directly or indirectly causes the thin plate to be perforated when such means is exposed to heat.

60

As the opening which is to be closed need only be some few millimeters in diameter, even a thin lead plate (wine bottle cap plate) can resist a very considerable boiler pressure, and but small force and motion is required for perforating such a plate.

65

An apparatus such as that described is exceedingly safe in operation and is to be preferred to an apparatus with a valve, which must close very tightly and which may stick 70 or fail to operate if permitted to remain in the same position for a considerable period.

Having thus fully described my invention, I claim as new and desire to secure by Letters Patent in U. S. A.—

75

1. An alarm device for indicating low water level in a boiler, comprising a casing adapted to communicate with the water space of a boiler, said casing having a passage therethrough, an alarm device secured 80 to said casing over the passage therein, a frangible diaphragm adapted to normally close communication between the casing and the alarm device, thermostatic means within the casing and means under control of said 85 thermostatic means and adapted to be projected against and to disrupt said frangible diaphragm upon the presence of unduly high temperatures within the casing.

2. In a device for indicating low water 90 level in a boiler the combination of a casing adapted to communicate with the water space of a boiler said casing having a passage adjacent to one end thereof, an alarm device engaging said casing over the passage 95 therein, a frangible diaphragm closing said passage and interposed between the casing and the alarm device, a rod movable in said passage and adapted to be projected against and to disrupt said diaphragm, a pivoted 100 double arm lever having one arm in position to engage said rod, and a thermostatic device engaging the other arm of said lever and for moving the same about its pivot.

In testimony whereof I have affixed my 105 signature in presence of two witnesses.

EIGIL AAGE HANSEN.
